Inventor:

Omar A. Stempel
By his atty
W. H. Price.

UNITED STATES PATENT OFFICE.

OMAR A. STEMPLE, OF ST. LOUIS, MISSOURI.

FIRE-EXTINGUISHER.

SPECIFICATION forming part of Letters Patent No. 511,469, dated December 26, 1893.

Application filed December 15, 1892. Serial No. 455,303. (No model.)

To all whom it may concern:

Be it known that I, OMAR A. STEMPLE, a citizen of the United States, residing at St. Louis, in the State of Missouri, have invented 5 a new and useful Fire-Extinguisher, of which the following is a specification.

My invention relates to chemical fire extinguishers, of the variety operated by an effervescent gas, created by mixing a strong acid, 10 with a soda solution.

The object of my present invention is first, to provide a strong, safe and durable chemical fire extinguisher, and second, to construct a chemical fire extinguisher, capable of automatic and instant operation when required for service.

To enable others skilled in the art to which my invention appertains, to make and use the same, I will now proceed to describe its construction and operation, reference being had to the accompanying drawings, which form a part of this specification, and in which—

Figure I. is a perspective view of my improved fire-extinguisher, Fig. II. is a vertical 25 section of the extinguisher, showing the outlet, the screen, the acid vessel in position, the manner of securing the cover to the main tank of the extinguisher, and the drop weight resting at the base of the main tank.

Similar letters indicate similar parts throughout the drawings.

A represents my improved chemical fire extinguisher, comprising the main tank B, having the spherical base C, the cover D, screen

35 E, acid vessel F, drop-weight G, out-let hole H, hose I and nozzle J as arranged in position for use. The spherical base C is so constructed, for the purpose of retaining the drop-weight G without danger of breaking the acid

40 vessel F, in the event the extinguisher should be laid upon its side, or tipped to an angle of forty-five degrees, for storing or in transit. It being understood, however, that in the nature of chemical fire extinguishers, instant operation 45 is effected by mixing the acid from the smaller vessel with the soda solution in the main-tank. Hence, the object of the drop-weight G normally contained in the spherical base C of the main tank B, is to fall upon and

50 crush through the acid vessel F when the extinguisher is tipped to an angle of seventy-five degrees, or entirely inverted, and thus automatically bring the extinguisher into instant operation. The drop-weight G in this 55 instance consists of a ball of sufficient weight

to break the acid vessel F under the conditions above described. Although, any suitably shaped weight of any serviceable metal may be used for this purpose.

The acid vessel F is of glass, round in shape 60 having thin flat sides, and so constructed, as to rest loosely upon rims, or shoulders formed in the main-tank B and cover C in the position shown in Fig. II.

The cover D is provided with a screen E of 65 wire-cloth, perforated metal, or any other suitable material, extending entirely across it, and located between the outlet-hole K and the acid vessel F as shown in Fig. II, for the purpose of keeping the outlet-hole free and 70 clear of glass or similar accumulations or obstructions.

The cover D is secured to the main-tank B by means of the male and female screw threads L. L'. The cover, when screwed home, rests 75 upon a rubber, or other suitable packing band M.

My improved extinguisher may be equipped with a suitable harness of proper material, made upon any of the plans commonly adopted for this purpose, for conveniently carrying the extinguisher while in use.

It will be observed that my improved extinguisher which can be cheaply constructed, is simple, strong and effective.

I do not lay broad claim in this application to my invention herein illustrated, as it is so claimed in my application, Serial No. 484,396, filed August 30, 1893.

Having thus fully described my invention, 90 what I claim, and desire to secure by Letters Patent, is—

A chemical fire extinguisher, comprising the cylindrical main-tank B, encircled at its top by the screw-thread L, and provided with 95 a spherical base C, arranged to receive and contain the weight G, the acid vessel F, located between the top rim of the main-tank B, and the right-angled off-set in the cover D, the cover D, having the screw-threaded rim 100 L', for securing it to the main-tank B, and provided with the screen E, located between the acid vessel F, and the out-let hole, the connecting hose I, and nozzle J, combined, applied and operating substantially as shown 105 and described.

OMAR A. STEMPLE.

In presence of—

W.M. H. OSMER,
CHAS. GUNDLACH.
